UNITED STATES PATENT OFFICE

EGERTON RYERSON CASE, OF TORONTO, ONTARIO, CANADA

ELECTRIC LIQUID HEATER

Application filed March 7, 1927. Serial No. 173,443.

My invention relates to improvements in electric liquid heaters, and the objects of my invention are: firstly, to produce a portable or stationary electric liquid heater having an ⁵ inlet and an outlet, and which can be readily uncovered to permit the removal therefrom of an unfettered base or support, and without the necessity of uncoupling any of the permanent electrical and liquid pipe-connections, thus making the device ideal for domestic use, since it requires practically no servicing; secondly, to associate the resistor or heating element in a preferred manner with the base or support; thirdly, to provide ¹⁰ an electric liquid heater that can be supplied with current from the ordinary base or wall outlet, thus dispensing with the necessity of any special electrical installation therefor; fourthly, when the base or support is made ¹⁵ in sections which are relatively axially movable, to removably tie the same together so that the base and the resistor carried thereby may constitute a unit repairable in any of its parts, and fifthly, to maintain an electrically ²⁰ highly-heated relatively-confined volume-constant body of fluid through which to pass a stream of confined liquid of a lower temperature in order to hasten rise in temperature thereof, and in the following specification ²⁵ and the drawings forming part thereof, I shall describe and illustrate several species within my invention, and what I claim as new will be set forth in the claims forming part of this specification.

³⁰ Fig. 1 is a vertical central section through the preferred form of heater. Fig. 2 is a horizontal cross section on the line 2—2, Fig. 1, and Fig. 3 is a horizontal cross section on the line 3—3, Fig. 1. Figs. 4, 5, 7, 10, 12, ³⁵ 13 and 21 are vertical central sections through alternative forms of the heater. Fig. 6 is a horizontal cross section on the line 6—6, Fig. 5. Fig. 7a is a sectional detail showing how the metal casing for the heating element may be packed where it passes through the ⁴⁰ cap of the base shown in Figs. 4, 5 and 7. Fig. 7b is a plan view of the cap of the base shown in Fig. 7 showing how the metal casing for the heating element comes through ⁴⁵ said cap. Fig. 8 is a horizontal cross section

on the line 8—8, Fig. 7. Fig. 9 is a horizontal cross section on the line 9—9, Fig. 7. Fig. 10a is a plan view of the cap of the base shown in Fig. 10. Fig. 11 is a horizontal cross section on the line 11—11, Fig. 10. Fig. ⁵⁵ 14 is a central longitudinal section through the support shown in Fig. 1. Fig. 15 is a plan view of Fig. 14 with the terminals removed. Fig. 16 is a side elevation of the support shown in Fig. 14, and Fig. 17 is a ⁶⁰ plan view of one of the sections of said support. Fig. 18 is a side elevation of a modified form of the support shown in Fig. 16, and wherein the support is integrally formed. Fig. 19 is a side elevation of one of the sections of the support shown vertically centrally in section in Fig. 7, and Fig. 20 is a ⁶⁵ vertical central section through a modified form of the topmost section of the support shown in Fig. 1. ⁷⁰

In the drawings, like characters of reference refer to the same parts.

Broadly considered, the invention preferably comprises an outer casing having an inlet and an outlet; an unfettered base or support therewith through which the liquid to be heated flows, and a resistor or heating element associated therewith: means at the upper end of said base or support, and having no connection with said outer casing, extending immediately over a central liquid passageway in said base or support and preferably relatively separable in respect thereto without having to dismantle the heater, and devoid of ⁷⁵ any liquid passage therethrough, and for the purpose of preventing any liquid flowing out of the upper end of said passageway longitudinally thereof, thus avoiding the use of a liquid chamber above said base or support, ⁸⁰ and necessary pipe connections therefor, and a projecting post at the upper end of said base or support directly or indirectly coupled thereto and preferably positioned laterally of the central passageway therein, which post ⁸⁵ carries the binding posts to which both ends of the said resistor or heating element are coupled. ⁹⁰

The invention further consists in the combination of parts hereinafter particularly de- ⁹⁵ 100

scribed and pointed out in the claims forming part of this specification.

In all species disclosed of this invention, the base or support is essentially removed from the outer casing through the top or outer end thereof according to the position of the heater.

I prefer to pass liquid interiorly and exteriorly of the base or support as this makes for greater efficiency, as is self-evident; and this I am able to do without passing any pipe connections for the liquid through the cover or cap of the heater, nor through the means which extends over the upper or outer end of the longitudinal passageway through said base. The advantage I obtain from the absence of any pipes or conduits through the parts referred to, is that I can readily remove the base or support when necessary, since I dispense with the use of a liquid chamber at the extreme upper or outer ends of the heater. It is self-evident that I provide a very compact construction and one that can be manufactured at reasonable cost.

The heating element or resistor may be of any well-known type. Where it is intended that it be directly immersed in water, it should be made from non-rusting material such, for example, as "sicro" which may be of approximately the following analysis: iron 75%; chromium 20%; silicon 2%; cobalt 2%; and carbon 3%, with small proportions of manganese and impurities, such as sulfur etc.

The heating element may also be of the type known in the art as "sheathed wire". This type of heating element may be briefly stated as consisting of a resistance core surrounded by a metallic envelope or sheath, with an intervening layer of powdered material, such as magnesia, which is a good electrical insulator, but a good conductor of heat.

Fuller particulars regarding the sheathed wire, may be had upon reference to Patent #1,107,233, which was issued to Chester N. Moore, August the 11th, 1914.

The preferred form of construction is illustrated in Fig. 1. The base or support 2 is preferably made in sections so that in case of breakage, any section may be readily replaced. The base is of course made of porcelain or any suitable insulating material. Each section is provided with a flange 3 which fits within a socket formed by an embracing flange 4 of the opposing section. Said sections are tubular in form, and the same are held together by a tubular, preferably metal, member 5 which passes centrally through said base. This tubular member 5 projects beyond both ends of the said base, and attached to the lower end thereof is an exteriorly positioned ring 6 which is partly located in a socket formed in the lowermost section of the base 2 as shown clearly in Figs. 1 and 14. A flanged member 7 is made of the same mate-

rial composing the base 2 and is mounted on the tubular member 5 since it has a central passage-way therethrough, and it rests in contact with the topmost section of the base 2. This flanged member 7 is provided with a flange 8 which embraces the flange 3 of the topmost section of said base 2. The flange 8 is used so that when the base 2 is removed any section thereof may be positioned in contact with the flanged member 7. Removably carried by the upper end of the tubular member 5 which projects above the flanged member 7, is a nut 9. The function of the nut 9 in co-operation with the member 5 and ring 6 is to hold the sections of the base 2 in co-operative relationship.

The sections of the base 2 are each provided with a plurality of spaced bars or ribs 10 extending longitudinally thereof, so that the resistor or heating element 11 may be "laced" longitudinally on said base, as will be understood upon referring to the arrows in Fig. 16. The upper ends of the ribs 10 forming part of the topmost section of the base 2 are spaced apart from the flanged member 7 so that the resistor 11 may be located between the said ends and the said flanged member. The lower ends of the ribs 10 of the lowermost section of the base 2 do not extend to the lower end of the flange 4 of said lowermost section, and therefore portions of the resistor or heating element 11 passing underneath the lower ends of the ribs of said lowermost section will rest in contact with said flange.

In order to tie the heating element or resistor 11 to the base 2 intermediate its end sections, after the resistor has been laced on the base, any of the intermediate sections of said base can be turned sufficiently so as to move the ribs or bars 10 thereof out of alignment with the ribs or bars of the other sections, so as to pinch portions of the resistor 11 between the ends of said bars or ribs. After this tying of the heating element or resistor 11 has been effected, the nut 9 can be tightened up and so hold the various sections of the base 2 in desired relative relationship. The ends of each rib or bar 10 are undercut as shown at 12 (Figs. 1 and 14), and the extremity 13 of each rib or bar projecting beyond the undercut portion thereof will come in contact with the resistor and act as a clamp to, in effect, tie the same to the base 2 as beforementioned.

Integrally formed with the flanged member 7 is a post 14, which preferably, though not essentially, projects above said flanged member 7. This post is provided with two passageways 15, one only of which is shown in Figs. 1 and 14, and through these passageways is passed the ends of the resistor 11 (see Fig. 1), which ends are secured to the binding posts 16 (only one of which is shown), which are carried by the post 14.

In Fig. 18, the base is made in one piece, and is provided with the flanged member 7 and nut 9 and tubular member 5, as well as the post 14. The form of base shown in Figs. 14 and 16 particularly, since the ribs or bars 10 of each section are spaced apart, permits selective paths between any given pairs of bars or ribs 10 to be utilized in order to locate the resistor or heating element 11 on preferred parts of the base. This method of associating the resistor or heating element with a base is fully disclosed in my co-pending patent application No. 51,302, supports for electric resistance elements. 15

17 (see Fig. 1) is a plate which forms the top of the liquid chamber 18 at the bottom of the heater. This plate is centrally apertured as shown at 19, and threaded in this aperture is a tubular member 20, the upper end of 20 which is closed by a cap 21 integrally formed therewith or as shown. The heating unit in Figs. 14 and 16 is positioned for use as shown in Fig. 1, by passing it over the tubular member 20, which tubular member is received by 25 the tubular member 5. The said heating unit rests upon the plate 17 through the medium of its ring 6.

Located within the tubular member 20 is a conduit 22 which is formed of a pipe bent 30 back upon itself, and having its discharge end 23 preferably located at the bottom of the tubular member 20 and discharging into the liquid chamber 18. This conduit is carried by pipe couplings 24, portions of which 35 project through the liquid chamber 18, and also through the outer casing 25 of the liquid heater. As shown in Fig. 1, the pipe couplings 24 are detachably coupled to pipe couplings 26 which are carried by any suitable 40 liquid tank 27.

The base 2, which comprises the heating unit, is surrounded by a liquid chamber composed of inner and outer walls 28 and 29, spaced apart to permit liquid to flow therebetween. The lower ends of the walls 28 and 29 are attached to the plate 17 as shown at 45 30 and 31, (as by brazing to make liquid tight joints) in such position that the passageways 32 formed in the plate 17 will conduct liquid 50 into said liquid chamber between the walls thereof. The upper ends of the walls 28 and 29 are suitably secured together to make a liquid tight joint, though of course it must be understood that said walls 28 and 29 may be 55 integrally formed, thus avoiding the necessity of joining them together at their upper ends.

Liquid enters the heater through pipe couplings beforementioned and then passes up 60 and down through conduit 22 and into the liquid chamber 18, whence it passes through the passageways 32 into the liquid chamber formed by the walls 28 and 29, and then out 65 of the heater through the pipe couplings 33,

opening through the wall 29, to the liquid tank 27.

From what I have just described it is clearly seen that I utilize simultaneously heat interiorly and exteriorly of the heating unit 70 already described.

The outer casing 25 is spaced apart from the outer wall 29 of the liquid chamber surrounding the heating unit, and the space between these parts is filled with any suitable 75 heat retaining material, such as asbestos or mineral wool, or powdered soap stone.

The outer casing 25 extends above the top of the liquid chamber surrounding the heating unit so that a cap or cover 34 may be 80 removably attached thereto. This cap or cover may be made in any suitable way so as to retain as much heat as possible within the heater.

The portion of the casing 25 projecting 85 above or beyond the heating unit is slotted as shown at 35 so as to permit the binding posts 16 to project laterally of the heater.

By removing the cap or cover 34 access is had to the heating unit, and the same may be 90 withdrawn from the heater for any purpose.

Since the tubular member 20 has threaded connection with the plate 17, this tubular member may be removed, and thus permit 95 access to the liquid passages in the heater for cleansing purposes.

As shown clearly in Fig. 3 the conduit 22 does not fill the tubular member 20, and therefore liquid will enter this tubular member and surround the conduit 22. When the liquid flowing as indicated enters the conduit 22 it is at its lowest temperature, and by the time it passes into the liquid chamber 18 its temperature will have been considerably raised so that by the time it flows out of the 100 heater through the pipe couplings 33, its temperature will be very high.

Since the liquid entering the tubular member 20 and surrounding the conduit 22 must pass out of said tubular member 20 through the opening through which it entered thereto, the conduit 22 will be surrounded constantly by a highly heated body of liquid, which may sometimes be changed into steam. 105

In the species shown in Fig. 4, the base 110 or support 36 is shown as made of metal, though it may be of made of porcelain or similar material, and it is shaped like an inverted cone with the top removed. The lower end of this base or support rests upon a plate 17' and within a flange 37 carried by 115 said plate. 38 is a liquid chamber having its lower end secured to the plate 17' so as to form a liquid tight joint. The upper end of this liquid chamber is reinforced by a ring 39, and it is covered by a cap 40 which is 120 preferably provided with a flange 41 which embraces said ring 39. The upper end of the base or support 36 is preferably thickened 125 as shown at 42 so as to permit screws 43 to 130

be received thereby, which screws couple the cap 40 to the said base or support.

Through the pipe couplings 24 liquid enters into a conduit 44 which is threaded 5 through the plate 17'. Liquid from this conduit passes into a coiled conduit 45 positioned within the said base or support 36 and passes thereout through the outlet 46 into the interior of said base or support 36. Liquid 10 passes from said base or support at its lower end through openings 47 formed in the plate 17' and into the liquid chamber 18 and thence through the passages 32 formed in said plate 17' into the liquid chamber 38. When the 15 heater is full of liquid, this liquid can pass from the top of the base or support 36 only through the openings 48. The heated liquid escapes through the pipe 33 which is mounted in the wall of the liquid chamber 38. 20 25 is the outer casing of this form of heater, and the same is spaced apart from the liquid chamber 38 and insulated therefrom as before described. This form of the heater is also provided with a removable cap or cover 25 34 which is also slotted to accommodate the binding posts 16.

Integrally formed with the base or support 36 are spaced short ribs or lugs 49, which are located near the lower and upper ends of 30 said base or support. The heating element or resistor disclosed in this type of heater is known in the art as sheathed wire, before referred to, and it is laced on the base or support 36 as before described using the ribs or lugs 49 for this purpose.

The liquid of course comes directly in contact with the casing for the resistor in this type of heater, and therefore I am enabled to dispense with the inner wall 28 40 of the liquid chamber shown in Fig. 1.

The cap 40 is provided with a post 14, and the ends of the resistor are coupled to the binding posts carried by this post.

In this form of my heater as well as in 45 the form disclosed in Figs. 5 and 7, where the liquid comes directly in contact with the heating element, or with the sheathing enclosing the same, a liquid tight packing must be provided in the cap for the sheathing.

50 A suitable liquid tight packing for the type of heating element or resistor *a* is shown in section in Fig. 7a. A chambered nut *b* is received by the cap 40, and through this nut passes one end of the heating element *a*. *c* 55 is a gland nut through which the end of the resistor *a* passes. This gland nut screws within the nut *b* and tightly compresses the packing *d* around the casing of the resistor *a* and effectually prevents leakage.

60 The conduit 45 rests within the base or support 36, and its upper end *e* is received by a socket *h* formed in the upper end of the conduit 44. When the cover 34 is removed, the base or support 36 can be removed from the 65 heater, and since the upper end *e* of the con-

duit 45 is removably held in the socket *h* of the conduit 44, the conduit 45 will be withdrawn from the heater at the same time as the base or support 36. By removing the screws 43 and disconnecting the ends of the resistor or heating element *a* from the binding posts 16, and retracting the gland nut *c*, the cap 40 may be removed from the base or support 36.

Interposed between the cap 40 and the upper end of the liquid chamber 38, and the ring 39, is any suitable packing to form a liquid tight joint, as will be understood.

The heating element or resistor *a* may be tied or clamped to the base or support 36 in any suitable manner. A convenient means for this purpose is in the form of split rings 50 positioned to embrace the said heating element mounted on said base or support. The lowermost of these rings may be supported by the lowermost ribs or lugs 49, and the uppermost one of said rings may be supported by lugs 52 forming part of said base or support 36.

In Fig. 5 the base or support 36' is provided with central passageways 53 and 54 at its lower and upper ends, and intermediate these passageways are formed passageways 55 in the walls of this base or support. This construction permits liquid to flow longitudinally and laterally throughout said base or support, and come directly in contact with the heating element or resistor *a*; which may be of the character described in respect of Fig. 4.

The lower end of the base or support 36' is received by the plate 17'', and in the upper end of this base or support is formed passageways 48' to permit fluid to freely flow laterally out of the upper end of this support.

38' is a liquid chamber containing the base or support 36', and the same is secured by a liquid tight joint to the plate 17''. 18 is the liquid chamber at the bottom of the heater into which the liquid primarily flows, and it passes thence through the passages 32 formed in the plate 17'' into the interior of the liquid chamber 38'.

The resistor *a* in this species of my invention is associated with the base or support 36' after the manner disclosed in Fig. 4, and is retained thereon by the split rings 50 which are very clearly shown in Fig. 6.

In the form shown in Fig. 7, the base or support 2' is made in sections. Each section is provided at its upper end with an external flange 3' which is internally threaded to receive an externally threaded flange 4' of the opposing sections: from the construction just described the said sections are united, and thus I do away with the tubular member 5 shown in the preferred form.

The base or support 2' is of course provided with a central passageway therethrough, and the heating element or resistor 130

a is in the form shown in connection with Figs. 4 and 5. The heating element or resistor *a* is disposed longitudinally of the base or support 2', and the ribs or lugs 49 are provided for the purpose set forth in connection with Figs. 4 and 5. The use of these ribs or lugs 49 is shown clearly in Fig. 19.

A plurality of split rings 50 are also used in connection with this form.

The base or support 2' rests upon a plate 17''' which forms the top of the liquid chamber 18, and this plate is apertured to permit liquid to flow from said liquid chamber into the interior of the liquid chamber 38 which is carried by the plate 17''' and brazed or otherwise secured thereto to form a liquid tight joint.

The cap 40' which covers the passageway in the base or support 2' is integrally formed with the topmost section of this base or support, and is constructed to permit the resistor or heating element to be held therein. It is also provided with a post 14.

The liquid to be heated enters into pipe couplings 24, and into a pipe or conduit 22 which is in the same form as that illustrated in Fig. 1.

In Figs. 10, 12 and 13 the heating element or resistor *a'* is in a form similar to the heating element or resistor *a*, and the same is disposed longitudinally of the bases or supports 2'' and located interiorly thereof at the time of manufacture of said bases or supports, since the same is made of metal. In each of the species disclosed in the said figures the caps 40'' are removably coupled to their respective bases or supports, as by means of screws 43.

The caps 40'' are made of metal and are provided with passages 58 therethrough (see Fig. 10a) through which the ends of the resistor are passed.

Each of these species is also provided with a removable cap or cover 34 so as to permit the base or support to be removed from the heater.

In Figs. 10 and 13 I show the base or support 2'' as mounted within a liquid chamber 38, and the cap 40'' of each of this species has threaded connection with the upper end of its associated liquid chamber. It will be noticed upon referring to Fig. 13 that the liquid chamber 38 is secured to the bottom 59 of the casing 25. The base or support shown in Fig. 12 rests directly upon the bottom of the casing 25, as is the case in the species shown in Fig. 13, and therefore I am enabled to dispense with the liquid chamber 18.

In the species shown in Figs. 5 and 10, the liquid enters directly into the bases or supports shown therein through the central passages 19. In Figs. 10 and 13 liquid escapes laterally from the upper end of the bases or supports 2'' through passages 48.

In Fig. 13 liquid enters into the base or

support shown therein at the bottom through a passage 60.

In the species shown in Fig. 12, the liquid circulates interiorly only of the base or support, and finds ingress and egress through the pipes 24 and 33 tapped into the wall of said base or support and in such location as not to interfere with the heating element or resistor.

One side of the casing 25 in the species shown in Fig. 12, is provided with a longitudinal slot 61 for the major portion of its length, and when the parts of the heater are assembled, an arcuate plate 62 is positioned over said slot and held in place by screws 63 and 64 to the bottom of the casing 25, and to the cap 34, respectively. When it is desired to remove the base or support in this species, the screw 64 is removed thus permitting the removal of the cap 34, and then the screw 63 is removed, thus permitting the removal of the plate 62. The heat retaining material within the casing 25 available through the slot 61, may be scraped away, then the pipes 24 and 33 will be removed together with said base or support. Obviously the said pipes will enter the slot 61 when the said base or support is being replaced.

The species shown in Fig. 12 shows the pipes 24 and 33 provided with any suitable rubber connections 65 which can be removed at will. In the species under consideration, the cap 40'' thereof has a liquid tight packing between it and the top of the base or support it is associated with.

From the foregoing part of the specification, it will be clearly understood that the means, such as the caps 40, 40' and 40'' at the upper end of each base or support has no connection whatsoever with the outer casing 25, and it extends immediately over the central liquid passageway in said bases or supports and is relatively separable in respect thereto when the caps or covers 34 are removed with the exception of the cap 40'. No liquid passage is formed in said means, and therefore I dispense entirely with a liquid chamber above or beyond the upper or outer end of any of said bases or supports. In some species, for instance, Figs. 1, 7 and 12, the said means completely closes the upper end of the central passageway through each of the said supports, whereas in Figs. 4, 5, 10 and 13, the said means diverts the liquid laterally out of said central passages.

In Fig. 20 a modified form of the topmost section of the base or support 2 is shown, wherein the post 14 and flanged member 7 are integrally formed therewith.

In Fig. 13 spacing members 66 are shown to keep the base or support in this species of the invention spaced apart from the wall of the liquid chamber 38. These spacing members may be secured to either the wall of said liquid chamber or to the outside of said base 123

or support, or may be integrally formed with the latter.

Though I prefer to associate the resistor or heating element longitudinally on the base or support as shown clearly, for example, in Figs. 1, 7 and 10, I may use a heating unit wherein the heating element or resistor is helically disposed thereon, and yet retain the advantages of an unfettered heating unit, and the absence of a liquid chamber at the extreme upper end of the heater.

In Fig. 21, the heating unit embraces a central core 70. The resistor or heating element 11 is wound around said central core, and then a tubular member 71 is slipped over the core 70 to retain the convolutions of the resistor in place. This tubular member 71 is slotted as shown at 72 to permit the resistor or heating element to be wound around the outside of said tubular member. A tubular member 73 is placed around the tubular member 71. To hold the said central core and tubular members together I utilize a cap 40''' and a bottom plate 74. The cap 40''' and the plate 74 are provided respectively with flanges 75 and 76, which fit around the upper and lower ends of the tubular member 73. The parts just described of the heating unit are made of suitable insulating material, such as porcelain, and in order to tie the various parts described together, I locate in the central passageway of the central core 70, the tubular member 5 which also passes through the cap 40''' and the plate 74. Preferably removably carried by the lower and upper ends of said tubular member are rings or nuts 6 and 9.

Formed in the cap 40''' are openings such as 15 of Fig. 1, to permit the ends of the resistor or heating element to be passed through said cap and attached to the binding posts 16 which are supported by a post 14. The construction just described provides a heating unit which can be readily removable since it is not attached in any manner to the other parts of the heater.

Within the tubular member 5 is the tubular member 20 of Fig. 1, and this tubular member contains the conduit 22. The walls 28' and 29' of the liquid chamber in this species are connected at their lower ends by liquid tight joints with the plate 17, which is apertured to permit the flow of liquid into said liquid chamber.

It is self-evident from what I have stated that I do not desire to be limited to any particular manner of associating any type of heating element or resistor with the base or support.

Though I have indicated that the liquid enters the heater through the pipes and couplings 24, it will be understood that the direction of flow of the liquid can be reversed without departing from the spirit of my invention. In that case, the liquid in the conduit 22 flowing into the pipe couplings 24

will have a higher temperature than that of the liquid in the other parts of the heater.

The prior art shews efforts to utilize the heated chambered core or interior of a base or support for a resistor, but since the liquid it is desired to heat flows at large therethrough at a speed substantially that of any other part of the liquid stream in the heater, this chamber is kept constantly flushed, and therefore no relatively volume-constant body of highly-heated fluid is available therein to be used as I use it, and for this very reason my preferred form of heater, and certain modifications thereof, though as simple in construction as any other, possess the maximum of efficiency and are very economical in current consumption.

Assuming the quantity of current consumed is constant in all species of the invention disclosed, it is conceivable that the species shown in Figs. 1, 7 and 21, would be the most efficient. In all of these species, there is no outlet for liquid at the upper or outer end of the tubular bases or supports therein shown, and since the conduits 22 are shaped and preferably terminate as shown, the passage of liquid therethrough does not flush the said bases or supports out, as would be the case were these conduits to terminate a short distance from the upper or outer closed ends of said bases or supports. Therefore the heat stored in the liquid or vapor within said tubular bases or supports will very largely accelerate the heating of the liquid passing through said conduits. This is an important feature of my invention.

Where there are openings or passages laterally from the bases or supports in certain of the species shown, these openings or passages are preferably of a capacity that will not permit the liquid to pass too rapidly from the interior of the said bases or supports. But of course the flow of the liquid therethrough will be ample to insure a steady flow of hot liquid through the outlet for the heater.

In this specification and the claims forming part thereof, the term "volume-constant" is used to mean that while there may be a change in the state of the fluid (this will of course depend upon the temperature thereof) within the chambered core or base, the said chamber will, in use, always be filled with a fluid because of the common inlet-outlet opening which is preferably directly in communication with the current of liquid passing through the heater.

The term "relatively-confined" is used herein to convey the idea of a body of fluid which while housed within a chamber having a common inlet-outlet opening has communication with the current of liquid flowing through the heater by means of said common opening, but yet is incapable of freely entering into the circulation thereof.

The term "confined stream" means a stream

of liquid passing through a conduit located in or passing through a chamber.

While I have specifically illustrated and described means to preferably utilize electrical energy as the source of heat (because it is safer and more widely available than gas), it must be understood that I may use gas as the source of heat, and that the utilization of any suitable means to generate heat from gas falls within the terms of my disclosure and of my claims.

While I have described what I consider to be the best embodiments within my invention, it must be understood that the principle thereof may be embodied in still other forms, and I require not to be limited beyond the requirements of the prior art and the terms of my claims.

What I claim as my invention is:

1. A heating unit for an electric liquid heater removable from a working location without having to disconnect any part of the circuit therefor, comprising a non-conducting base or support having a longitudinal liquid passage therein; an external post at the upper end of said base or support; a resistor or heating element with which said base or support is provided, the same having both its terminals supported by said post for separable connection with an outside coupling, and means at the end of said base or support, where said terminals are located, to prevent egress of liquid longitudinally thereof at the said end.

2. A heating unit for an electric liquid heater removable from a working location without having to disconnect any part of the circuit therefor, comprising a non-conducting base or support adapted to permit liquid to flow therethrough; an external post at the upper end of said base or support; a resistor or heating element associated with said base or support and having both its terminals supported by said post for separable connection with an outside coupling, and means, at the end of said base or support where said terminals are located, and separable in relation to said base or support and adapted to prevent issue from the interior thereof longitudinally thereof at the said end.

3. In an electric liquid heater, the combination with a casing having an inlet and an outlet for a liquid, of a complete heating unit removable therefrom without having to disconnect any part of the circuit therefor, comprising an unfettered non-conducting base or support adapted to permit liquid entering said casing to flow therethrough; an external post laterally positioned at the extreme outer end of said base or support, a resistor or heating element associated with said base or support and having its terminals both at the same end thereof supported by said post for separable connection with an outside cou-

pling, and external means, at the extreme outer end of said base or support where said terminals are located, to prevent egress of liquid longitudinally thereof.

4. In an electric liquid heater, in combination a longitudinal centrally chambered non-conducting base or support; a resistor or heating element associated with said base or support and having its terminals both at the same end thereof fastened externally thereof for separable connection with an outside coupling; means at the end of said base or support, where said terminals are located, to prevent egress of liquid longitudinally thereof at this end; an externally fed conduit located within the chamber of said support and of less capacity than said chamber; a liquid chamber surrounding said base or support and having an outlet, and a liquid chamber at the bottom of said heater communicating with said first-mentioned liquid chamber and into which one end only of said conduit immediately opens so as to avoid the flushing of the chamber of said support by liquid escaping from said conduit.

5. In an electric liquid heater, in combination a longitudinal centrally chambered non-conducting base or support; an external post at the upper end of said base or support; a resistor or heating element associated with said base or support and having both its terminals supported by said post for separable connection with an outside coupling; means at the end of said base or support, where said terminals are located, to prevent egress of liquid longitudinally thereof at this end; an externally fed conduit located within the chamber of said support and of less capacity than said chamber; a liquid chamber surrounding said base or support and having an outlet, and a liquid chamber at the bottom of said heater communicating with said first-mentioned liquid chamber and into which one end only of said conduit immediately opens so as to avoid the flushing of the chamber of said support by liquid escaping from said conduit.

6. In an electric liquid heater, in combination a longitudinal centrally chambered non-conducting base or support; an external post at the upper end of said base or support; a resistor or heating element associated with said base or support and having both its terminals supported by said post for separable connection with an outside coupling; means at the end of said base or support, where said terminals are located, and separable in relation to said base or support, to prevent egress of liquid longitudinally thereof at this end; an externally fed conduit located within the chamber of said support and of less capacity than said chamber; a liquid chamber surrounding said base or support and having an outlet, and a liquid chamber at the bottom of said heater communicating with said first-

mentioned liquid chamber and into which one end only of said conduit immediately opens so as to avoid the flushing of the chamber of said support by liquid escaping from said conduit.

7. In an electric liquid heater, in combination a liquid chamber provided with an ingress, and passages through the top thereof; a non-conducting tubular base or support removably resting upon said top and in communication with a central passage therein; a conduit fed from said ingress and located in said central passage and of less capacity than said central passage and having its outlet discharging immediately into said liquid chamber; a liquid chamber supported by the top of said first-mentioned liquid chamber and communicating therewith and having an outlet, and within which said base or support is removably located; a resistor or heating element associated with said base or support and having its terminals both at the same end thereof fastened externally thereof for separable connection with an outside coupling, and means, at the end of said base or support where said terminals are located, to prevent egress of liquid longitudinally thereout.

8. In an electric liquid heater, in combination a liquid chamber provided with an ingress, and passages through the top thereof; a non-conducting tubular base or support removably resting upon said top and in communication with a central passage therein; a conduit fed from said ingress and located in said central passage and of less capacity than said central passage and having its outlet discharging immediately into said liquid chamber; a liquid chamber supported by the top of said first-mentioned liquid chamber and communicating therewith and having an outlet, and within which said base or support is removably located; an external post at the upper end of said base or support; a resistor or heating element associated with said base or support and having both its terminals supported by said post for separable connection with an outside coupling, and means, at the end of said base or support where said terminals are located, to prevent egress of liquid longitudinally thereout.

9. In an electric liquid heater, in combination a liquid chamber provided with an ingress, and passages through the top thereof; a tubular member removably supported by said top in a central passage therein, and having a closed upper end; a tubular member removably enclosing said first-mentioned tubular member; a tubular non-conducting base or support through which said second-mentioned tubular member passes, the ends of which latter project beyond the ends of said base or support; means whereby said second-mentioned tubular member is coupled to said base or support, so that said base or support and said second-mentioned tubular member

may be readily separated from said first-mentioned tubular member; a resistor or heating element associated with said base or support and having its terminals both at the top thereof fastened externally thereof for separable connection with an outside coupling; a conduit fed from said ingress and located in said first-mentioned tubular member and of less capacity than the same and having its outlet discharging immediately into said liquid chamber, and another liquid chamber within which said base or support is removably located, communicating with said first-mentioned liquid chamber and provided with an outlet.

10. In an electric liquid heater, in combination, a non-conducting tubular base or support; a tubular member located within said base or support, and projecting beyond each end thereof; means carried by each end of said tubular member whereby it is coupled to said base or support, and a post at one end of said base or support adapted to carry binding posts.

11. In an electric liquid heater, in combination, a sectional non-conducting tubular base or support; a tubular member located within said base or support, and projecting beyond each end thereof, the sections of said base or support being externally longitudinally provided with spaced ribs, the opposing ends of the ribs of adjacent sections being spaced apart, and the said sections being individually axially movable to place their respective ribs out of alignment; means at each end of said tubular member to clamp said sections in adjusted position, and a post at one end of said base or support adapted to carry binding posts.

12. In an electric liquid heater, in combination, a non-conducting tubular base or support made of a plurality of tubular sections, each section at one end being provided with an internal flange, and at the other end with an external flange, the latter, when the sections are placed together, enclosing the internal flanges, and each being further externally provided with longitudinal spaced ribs; said sections when placed together being independently rotatable to move their respective ribs out of alignment with the ribs of any other section; tubular means passing through said base or support to clamp said sections together, and a post at one end of said base or support adapted to carry binding posts.

13. In an electric liquid heater, a sectional non-conducting tubular base or support; spaced longitudinally-disposed external ribs carried by each of the said sections, the opposing ends of the ribs of adjacent sections being spaced apart, and the said sections being individually axially movable to place their respective ribs out of alignment with the ribs of the other sections; means inter-

nally located in said base or support to hold the said sections in relative relationship, and a flange at one end of said base or support and from which the ends of the ribs of the adjacent section are spaced, and a post carried by said flange adapted to carry binding posts.

- 5 14. In an electric liquid heater in combination two spaced cylindrical walls forming a tubular liquid chamber having a supply inlet, and an outlet; an unfettered tubular base or support removably resting within the space surrounded by the inner of said spaced walls, and having a common inlet-outlet opening only adjacent the supply inlet for 10 said liquid chamber; means common to said liquid chamber and said tubular base to provide a supply of liquid therefor comprising a conduit extending into said tubular base and returning with its discharge end at the inlet-outlet opening thereof, and of less capacity 15 than the chamber in said base or support, and a resistor or heating element associated with said base or support and having its terminals both at the closed end thereof and fastened 20 externally thereof for separable connection with an outside coupling.

15. In an electric liquid heater, in combination a base or support with a chamber having an inlet-outlet opening only; a resistor 25 associated with said base; a conduit located within said chambered support and of less capacity than said chamber and arranged therein with its open end at said inlet-outlet opening so that liquid passing into and from 30 the open end thereof will not flush said chamber, and means whereby liquid is passed into said chamber and through said conduit from a common source, for the purpose specified.

16. In an electric liquid heater, in combination 35 a base or support with a chamber having an inlet-outlet opening only; a resistor associated with said base; a liquid chamber housing said base or support and having an outlet, and an externally-fed conduit located within 40 said chambered support and of less capacity than same and having its discharge end which is the supply for said liquid chamber located at said inlet-outlet opening, to prevent a current of liquid flowing through the chamber 45 in said base or support to flush same.

- 50 17. A heating unit for an electric liquid heater removable from a working location without having to disturb any part of the circuit therefor, comprising a non-conducting 55 base or support adapted to permit liquid to flow therethrough; a post-provided member at one end of said base or support; a resistor or heating element associated with said base or support with its terminals coupled to said 60 post, and means for coupling said post-provided member and said base or support together, thereby providing a heating unit all parts of which are firmly held together.

- 55 18. In an electric liquid heater, in combination 65 a chambered base or support having one

end closed; a heating element associated therewith; a liquid chamber, adapted to receive and discharge a liquid, housing said base or support, the chamber of which latter communicates therewith, and a conduit through which liquid flows housed within said base or support and of less capacity than same, and having its discharge end placed relative to the open end of the chamber therein so that liquid escaping from said discharge end will not flush the said chambered base or support leaving therein a substantially confined volume-constant body of heated fluid, for the purpose specified.

70 19. In combination a non-conducting tubular base or support; a separable member at the outer end thereof laterally carrying a post, and means whereby said member is coupled directly to said base or support.

75 20. In an electric liquid heater the combination with a centrally-apertured double-walled liquid chamber having an intake, the bottom of the inner wall being apertured and spaced apart from the bottom of the outer wall, and a resistance-element-provided tubular base or support closed at the outer end and located in said central aperture and resting upon said inner bottom and in communication with the space separating said bottoms, of conduit means providing the supply for 80 said liquid chamber located within said base or support and having its discharge end opening directly into said space separating said bottoms.

85 21. In an electric liquid heater, in combination a centrally-apertured liquid chamber having an outlet; a chamber to which said liquid chamber is coupled and from which it receives liquid; a tubular member, closed at one 90 end, centrally carried by and communicating with said second-mentioned chamber and located in said central aperture; a feed conduit located within said tubular member and of less capacity than same and arranged therein with its discharge end located at the open 95 end of said tubular member; and an unfettered tubular base or support encompassing said tubular member and resting within said central aperture, and a resistor or heating element associated with said base or support and having its terminals both at the closed end of 100 said tubular member and fastened externally thereof for separable connection with an outside coupling.
